AIR CONDITIONING SYSTEM

Walter L. Fleisher, New City, N. Y.

Application November 6, 1934, Serial No. 751,684

4 Claims. (Cl. 257—1)

This invention relates to methods of and means for conditioning the atmospheres of enclosures.

The general object of the invention is to provide a system for conditioning the air of an enclosure wherein people congregate, in which all air handled by the system is treated for purposes of temperature and humidity regulation, but which assures delivery to the enclosure of air at a comfortable temperature and proper relative humidity.

In accepted air conditioning practice, it is usual to condition a volume of air by passing the air through a cold water spray or over surface coolers through which a refrigerating medium is circulated. The treated air is thereby reduced to a temperature below its dewpoint, and its excessive absolute humidity precipitated. The air is then too cold for comfort, and also, at a relative humidity of about one hundred per cent, i. e., substantially saturated. Since this air cannot safely be introduced directly into the room or enclosure constituting the conditioned area, it must be reheated. The reheating is ordinarily accomplished by adding to the conditioned air a volume of air from the enclosure under proper regulation. As a result, a tempered mixture is formed at a comfortable temperature higher than that of the conditioned air and at a proper relative humidity, lower than that of the conditioned air.

A feature of this invention resides in the conditioning of all instead of part of the air handled by the air conditioning system, wherein all air passes over cooling surfaces, so arranged that the air leaving the surfaces is suitable for introduction to the enclosure, i. e., is at a temperature substantially above the dew point required for dehumidification and at a relative humidity substantially below saturation. To achieve this result, applicant utilizes a plurality of cooling surfaces, one surface covering the entire cross-sectional area of the conditioner casing, others covering desired portions of the cross-sectional area, predetermined in accordance with the results desired. Thus, one section of the cooling surface will cover the entire cross-section of the apparatus; one may cover only two-thirds; a third only one-third of the entire cross-section, and so on.

Another feature of the invention, therefore, resides in the provision of cooling surfaces, adapted to condition to varying degrees different proportions of a total volume of air handled by a unitary air conditioning apparatus. Also, by providing a combination of surface cooler units

covering different cross-sectional areas of the same apparatus through which all the air flows, a varying resistance to the flow of air is provided at different points in the apparatus. Thus, the air stream is automatically proportioned, so that different portions contact with the different cooler elements, and this makes for a simple method of conditioning to different degrees, different portions of the one volume of air.

A further feature provides for feeding under suitable control either a cooling medium under summer conditions or a heating medium under winter conditions to a series of coils serving to cool and dehumidify or heat an air stream passing through the apparatus, responsive to load conditions affecting the conditioned area.

Another feature provides for washing and, under desired conditions, humidifying the air to assure dust and dirt precipitation as well as humidification control, whenever such treatment of the air may be desirable.

Further advantages flowing from simplicity in construction, ease and economy of operation, and effectiveness of control, will be apparent from the following description of a typical form of carrying out the invention to be read in connection with the accompanying illustrative drawing, in which:

Fig. 1 is a diagrammatic view of an air conditioning system, fragmentarily illustrated, in which applicant's conditioning elements, of varying capacity and covering varying cross-sectional areas of the same conditioner, are employed, and

Fig. 2 is a diagrammatic fragmentary view of a modified form of coil arrangement in which coils of varying size are employed, the coils being arranged, as in Fig. 1, to cover different cross-sectional areas of the same conditioner.

Considering the drawing, similar designations referring to similar parts, numeral 3 designates an enclosure such as a theatre, store, railroad car, or other area to be conditioned. Air is delivered to the enclosure from conditioner 4 by fan 5 through one or more ducts 6; and air is returned from the enclosure for reconditioning through return duct 7. Outdoor air through intake 8 under control of dampers 9 and the return air under control of dampers 10, enter the conditioner 4 where the outdoor air and/or return air will be conditioned as to temperature and humidity. Dampers 9 and 10 may be controlled manually or suitably operated automatically. Usually, however, dampers 9 will never be permitted to fully close, so that a minimum volume of outdoor air will always be admitted, sufficient

to take care of the ventilation requirements of the enclosure 3.

The conditioner 4 is equipped with a plurality of cooling coils 11, 12, 13, 14, 15 and 16. The coils are supplied with refrigerant or other suitable conditioning fluid from a source of supply through supply conduit 17 and the refrigerant or conditioning medium is returned from the coils to said source through return conduit 18. While no refrigeration apparatus or the like is illustrated, it will be understood that the refrigerant or conditioning medium supplied to the coils is suitably reduced in temperature under summer operating conditions so that the temperature of the coil surfaces will be capable of dehumidifying air contacting therewith and produce a desired low temperature. Thus, cold brine or water will be supplied through conduit 17, or, if desired, a chemical refrigerant of suitable character will be fed into the coils and cool the air contacting with the coils by direct expansion.

In Fig. 1, the fluid will preferably be refrigerated water, under summer conditions, and the same supply conduit 17 may feed the sprays 19. Eliminators 20 remove entrained moisture from the air. The reheater 21 is used, under winter operating conditions and is fed with steam or other heating fluid from any suitable source of supply. The coils 11, 12, 13, 14, 15 and 16 are preferably made of light weight metal of high conductivity having extended surfaces for promoting heat transfer. Coils 11 and 12 extend from wall 22 of the conditioner casing into and cover about one third of the cross-sectional area of the conditioner. Coils 13 and 14 extend into about two-thirds of the distance between walls 22 and 23 of the case. Coils 15 and 16 extend the full distance between the walls 22 and 23 of the casing and cover the whole cross-sectional area of the casing. As a result, if the volume of air passing through the conditioner at any one time be considered a unit, then substantially one-third of the unit of air will contact with coils 11 and 12; the same third and an additional third will contact with coils 13 and 14; and the whole unit will contact with coils 15 and 16. Obviously, the first third, which contacts with all coils will be treated to a greater degree than the third which contacts only with coils 13-16; and the third which contacts only with coils 15 and 16 will be affected least of all. Thus, under summer operating conditions, with refrigerant at a prescribed low temperature circulating through the coils, and depending upon the relative amount of surface in each of the coils, some of the air will be intensively conditioned to a desired low dewpoint, whereas other portions of the air will be conditioned to a lesser degree or only relatively slightly affected. The intensively conditioned air will, therefore, be augmented in volume by the other air, and reheated to a higher desired temperature. For example, with outside conditions at 95 degrees dry bulb and 78 degrees wet bulb, the first third in the method described in connection with Fig. 1 may be reduced to 55 degrees dry bulb, one hundred per cent relative humidity. The second third may be reduced, for example, to a temperature of 68 degrees and a relative humidity practically saturated, and the third third may be reduced, for example, to a temperature of 81 degrees and a relative humidity much less than saturated. As a result, the final temperature of the air stream at the discharge end of the conditioner will be, for ex-

ample, 68 degrees F., which is much higher than 55 degrees, the temperature of the first third after conditioning, and at a relative humidity appreciably less than one hundred per cent. The introduction of this air within the enclosure will 5 make for desired conditions, which neither third, if alone introduced, would produce, even if circulation requirements were entirely disregarded.

The sprays 19 may be used for cleaning and humidifying the air under winter conditions. 10 The water fed to the sprays will be at a temperature suitable for humidification purposes. The coils 11-16, in winter, may be supplied with a heating medium, if desired, but the arrangement of coils, as heretofore described, has its 13 primary advantages under summer conditions, when it may condition all air handled by the system yet deliver the air at a comfortable temperature and proper relative humidity.

Although the coil arrangement may be manually controlled, a thermostat 24, responsive to temperature changes in the enclosure, may be provided to control the admission of refrigerant to the coils. Thus, valves 11a, 12a, 13a, 14a, 15a and 16a regulate the admission of refrigerant or 23 conditioning fluid to respective coils 11, 12, 13, 14, 15 and 16. Under summer operating conditions, whenever temperature conditions in the enclosure rise above a prescribed point, thermostat 24 causes valve 16a to open first. This valve 30 may operate, for example, at 5 pounds air pressure, whereas 15a will operate at 7 pounds, 14a at 9 pounds, 13a at 11 pounds, 12a at 13 pounds and 11a at 15 pounds. As more cooling is required, the thermostat will cause the valves successively to open to admit refrigerant and increase the total cooling effect, until under peak load conditions all coils will be receiving refrigerant. As load conditions decrease, the coils will successively be cut out in reverse order. 40

The admission of conditioning medium to the sprays is controlled by valve 25, which may be controlled manually or automatically in response to changes in humidity in the enclosure. Normally, this valve is closed during the summer 45 or dehumidifying periods. Under winter conditions, thermostat 24 controls the admission of steam to reheater 21, and, if desired, may control the admission of heating fluid to the coils in the same manner as it controls the admission 50 of refrigerant under summer conditions.

In Fig. 2, the coils 26, 27, 28, 29, 30 and 31 are of various sizes and capacities. Thus, while coils 28 and 29 extend across the whole cross-sectional area of conditioner 4, as do coils 30 and 31, they 55 present less surface and are of smaller capacity than coils 30, 31 and hence, have less effect upon a stream of air passing through the conditioner. Coils 26 and 27 are not only of different size and hence, of different capacity than the other coils, 60 but extend but partially across the conditioner. Therefore, applicant may vary coil sizes, present coils of varying surface and capacity, and utilize coils extending over the whole or part of the cross-sectional area of the conditioner, thereby 65 producing a desired final condition of temperature and relative humidity, due to varying effects of the different coils upon the air stream flowing through the conditioner.

If it is desired to have the resistance to passage of air through the conditioner substantially the same at every point throughout the cross-sectional area thereof, resistances such as 32 and 33 of Fig. 1 and 34 of Fig. 2, comprising, for example, screens of suitable mesh, perforated 75

plates, or the like, may be provided and positioned in portions of the conditioner not provided with coils. The resistances may be designed to afford resistance equal to, less than, or greater than that provided by adjacent coils covering equivalent cross-sectional area.

Although coils are shown, it is apparent that any equivalent arrangement of equivalent conditioning means may be utilized to achieve 10 equivalent results.

Since certain changes in carrying out the above process and in the constructions set forth, which embody the invention, may be made without departing from its scope, it is intended that all 15 matter contained in the above description or shown in the accompanying drawing shall be interpreted as illustrative and not in a limiting sense.

I claim:

- 20 1. In a system of air conditioning, a conditioner having an air inlet, an air outlet, tempering coils between the inlet and outlet, one of said coils covering a certain cross-sectional area of the conditioner, other of said coils covering different 25 cross-sectional areas of the conditioner, means in addition to said coils to equalize the resistance to air flow through all parts of the cross-sectional area of the conditioner.
2. In an air conditioning apparatus, a conditioner having an air inlet and an air outlet, tempering coils within said conditioner between said

inlet and said outlet, different of said coils covering different portions of the cross-sectional area of said conditioner, and means in addition to said coils for regulating the resistance to air flow through different portions of the cross-sectional 5 area of said conditioner.

3. In an air conditioning apparatus, a conditioner having an air inlet and an air outlet, a series of tempering coils within said conditioner between said inlet and said outlet, means for 10 passing a stream of air through said conditioner from said inlet to said outlet, said coils being arranged so that one portion of said air stream will contact with a relatively great amount of coil surface and so that another portion of said air 15 stream will contact with a lesser amount of coil surface, and means in addition to said coils for regulating the resistance to the flow through said conditioner of different portions of the air stream. 20

4. In an air conditioning apparatus, a conditioner having an air inlet and an air outlet, a plurality of tempering elements within said conditioner between said inlet and said outlet, different of said elements covering different portions 25 of the cross sectional area of said conditioner, and means in addition to said elements for regulating the resistance to air flow through different portions of the cross sectional area of said conditioner.
